Karl P. Lippin
ATTORNEY

UNITED STATES PATENT OFFICE.

BERTRAM F. RANCH, OF SEATTLE, WASHINGTON.

SAFETY COAT-HOOK.

1,276,414.

Specification of Letters Patent. Patented Aug. 20, 1918.

Application filed January 27, 1917. Serial No. 144,800.

To all whom it may concern:

Be it known that I, BERTRAM F. RANCH, a citizen of the United States, and a resident of Seattle, in the county of King and State 5 of Washington, have invented certain new and useful Improvements in Safety Coat-Hooks, of which the following is a full, true, and exact specification.

My invention relates to safety coat hooks 10 and has for its principal object: to provide an improved and novel coat hook which automatically locks under the influence of the weight of the coat; to provide a device of the class described which embodies a coat 15 hanger which is normally open and ready to receive the coat, and which grasps the material of the coat firmly, thereby preventing the coat being removed from the hook while the hook is in locked position.

20 Other objects will appear as my invention is more fully explained in the following specification, illustrated in the accompanying drawings and pointed out in the appended claim.

25 In the drawings, Figure 1 is a side elevation of my device with parts broken away. Fig. 2 is a front elevation of the same.

Referring more particularly to the drawings, numeral 1 indicates a casing which is 30 secured to a wall, or the like. A standard 2 projects above the casing 1, and is hinged at its upper end to receive a closing lever 3. The lever 3 in addition to being hinged at one end to standard 2, is pivotally secured 35 adjacent its center point to a fulcrum angle 4. Angle 4 is rigidly attached to a hook 5, which is provided with an upturned forward end 6, and a downwardly bent rear end 7. The downwardly bent rear end fits slidably 40 in a slot 8, which is cut in the top of casing 1. Guides 9 also assist in retaining the portion 7 of the hook which projects within the casing 1. Along one edge of downwardly extending portion 7 a series of notches 10 45 are cut and are adapted to receive the end of a locking spring 11. While applicant shows a very simple type of locking spring, yet it will be apparent that many standard forms of locking devices might be incorporated in

place of the spring 11 and notches 10. A 50 spring 12 normally holds the hook 5 and lever 3 in position as shown in the drawings and is of sufficient strength to return the said members to a normal position when the weight of the garment which is hung upon 55 the hook has been released. The adjacent ends of lever 3 and the upstanding portion 6 of the hook are provided with rubber or other resilient tips 13 which firmly grasp the material of the garment. A flexible tape 60 14 connects the adjacent ends of lever 3 and the upstanding portion 6 of the hook, thereby providing a receptacle for the coat collar or hanger strap of the coat, which may assist in closing the hook. In operation the collar 65 of the coat is inserted between the adjacent ends of the hook and lever, and the weight of the coat is sufficient to force the hook downwardly within casing 1, thereby gripping the material of the coat, which finally 70 stops the downward movement of the hook. The spring 11 will engage one of the notches 10, thereby preventing the release of the coat until the spring 11 has been forced back by means of a key which is inserted through a 75 key-hole 15 in casing 1.

While I have shown a particular form of embodiment of my invention, I am aware that many minor changes therein will readily suggest themselves to others skilled in the 80 art without departing from the spirit and scope of the invention, and I therefore desire to avoid being limited to the exact form shown and described.

Having described my invention, what I 85 claim as new and desire to protect by Letters Patent, is:

In a device of the class described the combination of a stationary casing, a hook provided with an upturned end and a downwardly turned rear end the latter of which is slidably mounted in said casing, a closing lever hingedly mounted at one end upon said casing and positioned above said hook, an angle secured to said hook and pivoted to 90 said lever intermediate its ends, the outer end of said hook and the said lever being arranged in spaced relationship to each other 95

and adapted to be drawn in contact with each other when the hook is forced downwardly within the casing under the influence of the weight of the coat which is placed upon the hook, and automatically locking means, whereby when the hook is forced down within the casing it is retained in the

forced down position, said locking means including a spring secured to the inside of said casing and its free end coöoperating with 10 notches in the downwardly extending end of said hook.

BERTRAM F. RANCH.
